UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

CALL-REGISTERING SYSTEM.

1,354,051.

Specification of Letters Patent. Patented Sept. 28, 1920.

Application filed September 30, 1918. Serial No. 256,232.

To all whom it may concern:

Be it known that I, ALBEN E. LUNDELL, a citizen of the United States, residing at New York, in the county of Bronx, State 5 of New York, have invented certain new and useful Improvements in Call-Registering Systems, of which the following is a full, clear, concise, and exact description.

This invention relates to an improvement 10 in telephone systems and has particular reference to a service registering system for party lines, wherein calls originating in any one of a number of substations are registered and charged to the stations initiating 15 said calls.

In registering systems for polystation lines of known construction, means have been provided for selecting a register magnet individual to a calling subscriber's substation as a result of an initiated call. In 20 order to energize the selected magnet to complete a registration of the call, further means have been provided which are operated at the completion of the talking connection either by an operator or by the act 25 of the called subscriber in removing his receiver. Systems have also been devised wherein register magnets employed with single party lines have been operated by 30 reversal of current.

It is proposed, in the present invention, to provide a plurality of subscribers' substations with individual register means selectable upon the initiation of a call and operated by a reversal of current to register said 35 call.

Another object resides in the provision of means for reversing the current through the magnet of the selected registering means 40 and thereby operating the same when the connection between the calling and called subscribers is established by the latter performing some act such as removing his receiver.

45 The inventive idea involved is capable of receiving a variety of expressions, one of which, for the purpose of illustrating the invention, is shown in the accompanying drawing; but it is to be expressly understood that said drawing is employed merely for illustrating the invention as a whole and not to define the limits thereof, reference being had to the appended claims for this 50 purpose.

The drawing illustrates diagrammatically 55 the circuits for controlling a two-party line system and the selection and operation of the registering means individual to each line.

Referring more particularly to the drawing, A and B represent two subscribers' substations on a party line, and C, a called subscriber's apparatus. A differential relay 1 is associated with both sets A and B, and is energized or not, depending upon 60 which of the subscribers initiates a call. The registering mechanisms A' and B' are provided for the respective substations A and B, and should the subscriber at A establish a connection, relay 1 will remain 65 deenergized and a circuit will be prepared for the differential or electrically polarized magnet a' of the register A'. If the subscriber at B initiates a call then relay 1 is energized, cutting out the magnet a' and extending the circuit through the differential magnet b' of the register B'. The magnets a' and b' are not, however, energized at this time to pull up their respective armatures a² and b², which are not operated until the 70 called subscriber at substation C removes his receiver, at which time current is reversed through the selected magnet in a manner to appear in the course of the description, whereupon the particular register 75 is operated to charge the call to the individual calling subscriber.

A detailed description of the operation is as follows:

Should the subscriber at substation A initiate a call by removing his receiver from its hook, a circuit will be established from grounded battery, through the right winding of differential relay 1, winding of the slow release relay 2, back contact and inner 90 left armature of magnet 3, conductors 4 and 5, substation apparatus A, conductors 6 and 7, outer left armature and back contact of the magnet 3, left winding of differential relay 1 to battery and ground. The windings of relay 1 being opposed, the relay will 95 not pull up its armatures and the circuit through the conductor 7 will consequently be extended through the conductor 8, right-hand winding of the differential magnet a', conductor 9, back contact and left armature of relay 1, to terminal 10 of the line switch D. Slow release relay 2 will be 100 105

- energized by the circuit through it and will attract its armature. Ground being found upon the back contact of the armature of a relay E at the master switch, a circuit is closed for the magnet 3 which extends from grounded battery, through the right winding of magnet 3, armature and front contact of relay 2, and armature and back contact of master switch relay E to ground.
- 5 Magnet 3 will pull up the plunger 11 of the line switch and extend the circuit over the limbs 12 and 13 of the party line to permit of the operation, by the calling subscriber, of selector switches (not shown) which may be employed in setting up a connection, and since these switches form no part of the present invention, a detailed description thereof is believed unnecessary. Magnet 3 also attracts its left-hand armatures, breaking the circuit for the relay 2, but due to the fact that this relay is slow to release, the armature thereof will not be immediately retracted. When the line is extended to the first selector switch above referred to, a ground is found at said switch which completes a holding circuit for the magnet 3 extending from grounded battery, left winding of magnet 3, conductor 18 to said ground at the selector switch.
- 10 Upon extending the connection to the connector switch at the right of the drawing by the operation of the selector switches previously referred to, the relay 14 at the connector F is energized by a circuit extending from grounded battery, left-hand winding of relay 14, outermost back contact of relay 15, conductors 12, 4 and 5, substation apparatus A, conductors 6, 7 and 8, right winding of magnet a', conductor 13, innermost back contact and armature of relay 15 and through the right winding of relay 14 to ground. Relay 14 on energizing attracts its armature and establishes a circuit for slow-to-release relay 16, extending from grounded battery, winding of relay 16, front contact and armature of relay 14 to ground. Relay 16 attracts its armature and places ground upon the conductor 17 which extends to the selector switch last operated in a well-known manner. A holding circuit for magnet a' is also established which extends from grounded battery, left winding of magnet a', conductor 19, wire 17, armature and front contact of relay 16 to ground, and the right winding now being opposed to the left winding, this circuit prevents the armatures of said magnet a' from being attracted at this time.
- 15 The connector switch F is then set in the usual manner in operative relation to the called subscriber's line at substation C, and in the event that said line is not busy, a connection will be established for signaling the called subscriber in the usual manner.
- 20 The subscriber at substation C upon re-
- moving his receiver, energizes the relay 15 through a circuit extending from grounded battery, left-hand winding of relay 15, through substation apparatus, right-hand winding of relay 15 to ground. Relay 15 70 attracts its armatures, the contacts of which are of the make-before-break type. The energization of relay 15 causes a reversal of the current through the talking circuit which now extends from grounded battery, left 75 winding of relay 14, inner armature and front contact of relay 15, conductor 13, left armature and back contact of relay 1, conductor 9, right winding of magnet a', conductors 8, 7 and 6, substation apparatus A, 80 conductors 5, 4 and 12, outer armature and front contact of relay 15, right-hand winding of relay 14 to ground. As previously explained, the register magnet a' is not energized until the called subscriber answers 85 by removing his receiver, but upon the reversal of the current through the right winding of said magnet, the same will become energized and attract its right armature to complete the talking circuit and shunt the 90 conductor 8. The left armature a² of the magnet will also pull up and thus operate the register mechanism A'. A holding circuit for the magnet a' is established which extends from grounded battery, left winding of magnet a', conductor 19, wire 17, armature and front contact of relay 16 to ground.
- 95 If the subscriber at substation B initiates a call, a circuit will be established through 100 differential relay 1 in the same manner as described in connection with the initiation of a call at substation A but, owing to the fact that the signaling mechanism at substation B is grounded, the windings of the 105 relay 1 will become unbalanced and its armatures attracted. The left armature will break the circuit to register magnet a' and prepare a circuit for the register magnet b' of the register B', which extends from 110 grounded battery, the right winding of relay 1, winding of relay 2, back contact of the inner left-hand armature and magnet 3, conductors 4 and 5, substation apparatus B, conductors 6, 7 and 20, left winding of 115 magnet b' conductor 21, front contact and left armature of relay 1 to the line switch D. The circuit is extended to the selector and connector switches in the same manner as described in connection with a call from 120 substation A and upon the grounding of the wire 17 at the front contact and armature of relay 16, a locking circuit will be established for relay 1, extending from grounded battery, right winding of relay 125 1, right armature and front contact thereof, conductors 22 and 19, wire 17, armature and front contact of relay 16 to ground. A circuit is also extended from grounded battery, right winding of register magnet b' 130

conductors 22 and 19, wire 17, armature and front contact of relay 16 to ground. After the called subscriber has completed the connection, as by removing his receiver, the 5 current is reversed through the left winding of magnet b' , thus causing the magnet to become energized and pull up its armatures. Its left armature completes the talking circuit and its right armature operates 10 the register B' to charge the call to the subscriber at B substation.

At the termination of the call in either instance the connector switch may be returned to normal in any manner well known in the 15 art. Relay 15 also is deenergized, permitting its armatures to fall off and upon the deenergization of the relay 14, relay 16 falls off, removing ground from the wire 17, which may in the usual manner cause the 20 selector switches to return to normal. This results in the deenergization of line switch magnet 3 and of the magnet a' or b' which was selected upon the initiation of the call. Ground being also removed from the locking 25 circuit of the relay 1, in the case of a call from substation B, said relay will be deenergized and retract its armatures, whereupon the parts will all be in normal position.

30 For the purpose of signaling either of the two substations A and B as called lines after a connector switch G has established a connection between a calling subscriber and one of said substations, a ringing generator 23, shown at the left of the figure, is connected 35 to the circuit, and in the normal position shown, the signaling mechanism of substation B will be operated by a circuit extending from the generator, back contact and 40 right armature of relay 24, conductor 6, apparatus of substation B, and through the ringer thereof to ground. In signaling substation A, the relay 24 is energized in a manner well known in the art and the circuit is 45 extended from generator 23, front contact and left armature of relay 24, conductor 5, apparatus of substation A, conductor 6, right armature and front contact of relay 24 to ground.

50 What is claimed is:

1. In a telephone system, a party line having a plurality of substations, a register mechanism individual to each of said substations, means for selecting one of said 55 mechanisms upon the initiation of a call at the associated substation, and means for reversing the current through said register mechanism to cause the operation thereof.

2. In a telephone system, a party line having a plurality of substations, a register mechanism individual to each of said substations, means for selecting one of said mechanisms upon the initiation of a call at the associated substation, and means actuated 60 upon the completion of a connection for

reversing the current through said register mechanism to cause the operation thereof.

3. In a telephone system, a party line having a plurality of substations, a register mechanism individual to each of said substations, means for selecting one of said mechanisms upon the initiation of a call at the associated substation, and means automatically actuated upon the completion of a connection for reversing the current through 70 75 said register mechanism to operate the same.

4. In a telephone system, a party line having a plurality of substations, a register mechanism individual to each of said substations, means for selecting one of said 80 mechanisms upon the initiation of a call at the associated substation, and means actuated upon the removal of the receiver of a called subscriber's station for reversing the current through the selected register mechanism to cause the operation thereof.

5. In a telephone system, a party line having two substations, a register mechanism individual to each substation and including a magnet, means for selecting one of said 90 magnets upon the initiation of a call at the associated substation, and means for reversing the current through said magnet to energize the same and operate said register mechanism.

6. In a telephone system, a party line having two substations, a register mechanism individual to each substation and including a magnet, means for selecting one of said 100 magnets upon the initiation of a call at the associated substation, and means for reversing the current through said magnet upon the completion of a connection to energize the same and operate said register mechanism.

7. In a telephone system, a party line having two substations, a register mechanism individual to each substation and including a magnet, means for selecting one of said 110 magnets upon the initiation of a call at the associated substation, and means automatically actuated for reversing the current through said magnet to energize the same and operate the register mechanism.

8. In a telephone system, a party line having two substations, a register mechanism individual to each substation and including a magnet, means for selecting one of said magnets upon the initiation of a call at the associated substation, and means actuated upon the removal of the receiver of a called substation for reversing the current through 120 125 said magnet to energize the same and operate the associated register mechanism.

9. In a telephone system, a party line having a plurality of substations, a register mechanism individual to each of said substations, means for selecting one of said mechanisms upon the initiation of a call at 130

the associated substation, and a relay for reversing the current through said register mechanism to cause the operation thereof.

10. In a telephone system, a party line having a plurality of substations, a called line, a register mechanism individual to each of said substations, means for selecting one of said mechanisms upon the initiation of a call at the associated substation, and a relay in circuit with the called line for reversing the current through said register mechanism to cause the operation thereof.

11. In a telephone system, a party line having a plurality of substations, a called line, a register mechanism individual to each of said substations, means for selecting one of said mechanisms upon the initiation of a call at the associated substation, and a relay in circuit with the called line and energized upon the completion of a connection to reverse the current over said line and through said register mechanism whereby to cause the operation thereof.

12. In a telephone system, a party line having a plurality of substations, a register mechanism individual to each substation and including a magnet adapted to be energized to operate said mechanism, means for selecting one of said magnets upon the initiation of a call at the associated substation, and a relay for reversing the current through said magnet to energize the same.

13. In a telephone system, a party line having a plurality of substations, a register mechanism individual to each substation and including a magnet adapted to be energized to operate said mechanism, means for selecting one of said magnets upon the initiation of a call at the associated substation, and a relay operated upon the completion of a connection to reverse the current through said magnet and energize the same.

14. In a telephone exchange, a party line having two calling subscribers' substations, a register magnet individual to each substation, a called subscriber's substation, means for selecting one of said magnets upon the initiation of a call at the associated calling subscriber's substation, means for connecting said calling subscriber's substation to the called subscriber's substation, and a relay operated upon the removal of the receiver at the called subscriber's substation for reversing the current through the selected magnet, whereby the same is energized.

15. In a telephone system, a party line having a plurality of substations, a register mechanism individual to each, means for selecting one of said mechanisms upon the initiation of a call at the associated substation, and electromagnetic means for reversing the current through said mechanism to operate the same.

16. In a telephone system, a party line

having a plurality of substations, a register mechanism individual to each of said substations, means common to said substations for selecting one of said mechanisms upon the initiation of a call at the associated substation, and means for reversing the current through said register mechanism to cause the operation thereof.

17. In a telephone system, a party line having a plurality of substations, a register mechanism individual to each of said substations, a single means for selecting one of said mechanisms upon the initiation of a call at the associated substation, and means actuated upon the completion of a connection for reversing the current through said register mechanism to cause the operation thereof.

18. In a telephone system, a party line having a plurality of substations, a register mechanism individual to each of said substations, an electromagnetic device for selecting one of said mechanisms upon the initiation of a call at the associated substation, and means automatically actuated upon the completion of a connection for reversing the current through said register mechanism to operate the same.

19. In a telephone system, a party line having a plurality of substations, a register mechanism individual to each of said substations, a differential relay for selecting one of said mechanisms upon the initiation of a call at the associated substation, and means actuated upon the removal of the receiver of a called subscriber's station for reversing the current through the selected register mechanism to cause the operation thereof.

20. In a telephone system, a party line having two substations, a register mechanism individual to each substation and including a magnet, a single means common to said substation for selecting one of said magnets upon the initiation of a call at the associated substation, and means for reversing the current through said magnet to energize the same and operate said register mechanism.

21. In a telephone system, a party line having two substations, a register mechanism individual to each substation and including a magnet, means independent of said substations for selecting one of said magnets upon the initiation of a call at the associated substation, and means for reversing the current through said magnet upon the completion of a connection to energize the same and operate said register mechanism.

In witness whereof, I hereunto subscribe my name this 6th day of September, A. D. 1918.

ALBEN E. LUNDELL.
